DESIGN FOR A DENTAL SUPPLY KIT

Katharine G. Van Dyk, Scarsdale, N. Y.

Application October 11, 1947, Serial No. 141,875

Term of patent 14 years

(Cl. D58—11)

To all whom it may concern:

Be it known that I, Katharine G. Van Dyk, a citizen of the United States of America, residing at Scarsdale, county of Westchester, and State of New York, have invented a new, original, and ornamental Design for a Dental Supply Kit, of which the following is a specification, reference being had to the accompanying drawings, forming part thereof.

Fig. 1 is a front perspective view of a dental supply kit, showing my new design;

Fig. 2 is a top plan view thereof;

Fig. 3 is a side elevational view as seen from the right of Fig. 1; and

Fig. 4 is a front elevational view of the tooth paste tube shown removed from the container.

The back of the container and the back of the tooth paste tube are not decorated.

The other side of the container has the same

appearance as the side shown in Fig. 3, except that the tooth brush extends thereabove.

The handle of the tooth brush is of conventional shape and is not decorated.

I claim:

The ornamental design for a dental supply kit, as shown and described.

KATHARINE G. VAN DYK.
